Primary Examiner — Jennifer L Rempfer(74) *Attorney, Agent, or Firm* — Craft Chu PLLC;
Andrew W. Chu(57) **CLAIM**

The ornamental design for a neck support pillow, as shown and described.

DESCRIPTION

FIG. 1 is a side perspective view of the neck support pillow showing my design with a loop and scarf in broken line portions and a dashed seam line.

FIG. 2 is a front elevation view thereof showing the loop and scarf in broken line portions and a dashed seam line;

FIG. 3 is a back elevation view showing a strip pattern, the loop and scarf in broken line portions and dashed seam lines;

FIG. 4 is a back elevation view showing the loop in a broken line portion and a dashed seam line;

FIG. 5 is a side elevation view thereof, showing the loop and scarf in broken line portions and a dashed seam line;

FIG. 6 is an opposite side elevation view thereof, showing the loop and scarf in broken line portions and a dashed seam line;

FIG. 7 is a top plan view thereof, showing the strip pattern, the loop and scarf in broken line portions and dashed seam lines; and,

FIG. 8 is a bottom plan view thereof, showing the strip pattern, the loop and scarf in broken line portions and dashed seam lines.

The broken line portions in FIGS. 1-8, showing a strip pattern, a loop, and a scarf with optional holes, are presented for illustrative purposes and form no part of the claimed design.
